PUMP

Roy Stevens, Detroit, Mich.

Application December 8, 1938, Serial No. 244,509

9 Claims. (Cl. 103—162)

This invention relates generally to pumps or compressors and more particularly to the operating mechanism therefor.

One of the objects of the present invention is to provide a new and improved pump or compressor having new and improved driving means arranged to materially reduce friction in the pump.

Another object of the invention is to provide a pump having a new and improved arrangement of the operating parts thereof.

Other objects of the invention will become apparent from the following description taken in connection with the accompanying drawings in which

Figure 1 is a longitudinal sectional view of my improved pump;

Fig. 2 is an end view of a plurality of pump cylinders;

Fig. 3 is a view shown in cross section of the pump driving mechanism, taken along the line and in the direction of the arrows 3—3 of Fig. 1, and

Fig. 4 is a view in section of the pump taken along the line and in the direction of the arrows 4—4 of Fig. 1.

Referring to the drawings by characters of reference, there is shown a multiple pump which includes a casing 10 of tubular form having a right angle turn or bend intermediate its ends, the casing preferably being constructed of two longitudinal sections which may be rigidly secured together by bolts and nuts 11, or by other suitable means. In the casing 10 adjacent each end thereof, is a multiple pumping unit, which includes a plurality of parallel open ended cylinders 12 of which there are six in each unit, in the present instant. The cylinders 12 are radially spaced about a central spacer-bearing member 13 to which the cylinders may be rigidly secured, such as by welding, or with which the cylinders may be cast integral, if desired. The outer ends of the cylinders 12 and their respective spacer-bearing members 13 are flush with each other and fitted over the outer ends thereof is a plate-like cap member 14, Fig. 1, which may be welded or otherwise secured to the cylinders and to the bearing members 13. The cap member 14 is provided with a plurality of radially spaced ports 15 which register one with each of the outer cylinder ends.

Removable end walls or header members 16 are rigidly secured, one to each end of the casing, in abutting relation with the outer surfaces of the cap members 14 and each of the end walls

is provided with an inlet 17 and an outlet 18. The cylinders 12 of each unit are rotatable with and about the longitudinal axis of their respective spacer-bearing members 13 in the outer end of each of which may be secured a shaft 20 which may be journaled for rotation in bored recesses 22 in the casing end walls 16. The shafts may be secured to their respective spacer-bearing members 13 by a transverse pin 21 or by any other suitable means. In the inner ends of each of the end walls 16 is provided a pair of arcuate slots or grooves 23, 24, which communicate with the inlets 17 and 18 respectively and which are arranged to register with the radially spaced ports 15 of the rotatable cylinder units, as shown in Fig. 4.

Disposed in the casing 10 is a shaft 25 having end portions 25a at right angles to each other supported in the inner ends of the spacer-bearing members 13 and the shaft 25 is provided, substantially midway of its ends, with a bearing portion 26, arranged with its longitudinal axis at an angle of 45° with respect to the axes of rotation of the cylinder units. In the tubular spacer members 13 are provided, thrust bearings 27 engaging in sockets in the ends of the shaft 25 and in bearing retainers 28. Disposed in each of the tubular spacer members 13 is a helical coil spring 30 having one end in abutment with the bearing retainer and the other end in abutment with the inner end of the rotatable shaft 20, the spring 30, in addition to retaining the bearings 27 in their sockets, urge the cylinder units outwardly to hold the abutment plates or caps 14 in tight abutting relation with the inner wall surfaces of the casing end walls 16 to prevent leakage between the abutting surfaces.

Disposed in the casing 10, a plurality of radially spaced rod-like piston members 32 is provided having end piston portions 25a received in the cylinders 12, the piston portions of each piston being at right angles to each other. The pistons 32 are formed midway of their ends with crank or bearing portions 33 which are parallel to each other and to the shaft bearing portion 26 and are therefore at 45° or acute angles to the axis of rotation of the cylinder units. In order to decrease friction in a pump or compressor of this character, the driving force is applied to the pistons midway of their ends, the parallel piston portions or cranks 33 being rotated about the axis of the shaft portion 26. With the piston portions or cranks arranged at acute angles to the axis of rotation of the cylinder units it will be seen that in order for the pistons to operate

the piston portions or cranks 28 on rotation about the shaft portion 26 must travel through an elliptical path, see Fig. 3.

A plurality of radially disposed crank members 5 or hollow spokes 35 which form in part, slip clutch members, are provided and at their inner ends have arcuate or convex bearing surfaces 36a arranged to bear against the shaft portion 26. The crank members 35 are each provided 10 with an elongated opening 36 extending longitudinally thereof providing slideways for slidably receiving and guiding bearing members 38 in each of which one of the piston portions 33 is journaled for rotation. The outer ends of the 15 cranks 35 are recessed, as at 39, to receive in each a spring pressed ball clutch member 40, and the recessed wall of the cranks is curved and tapered for cooperation or wedging action with the balls 40 which also cooperate with the inner wall surface 20 face of a driven or rotatable ring gear 41, which surrounds the cranks, and to which the cranks are coupled and uncoupled during operation of the pump. The ball clutch members 40 are individually urged in the direction of rotation of 25 the ring gear 41 by helical coil springs 40a disposed in the recessed ends of the crank members 35. The ring gear 41 may be driven by a worm gear 42 or by any other suitable means.

In operation of the pump, the ring gear 41 is 30 rotated at constant speed by the worm gear 42 and in each of the pump units, two pairs of the opposite cranks 35 are coupled to the ring gear 41, rotating the piston portion 33 and imparting reciprocation thereto. Only two pairs of the 35 cranks 35 are coupled to the ring gear at any one time, the other pair of cranks being free as a result of slippage with the ring gear. However, successive pairs of cranks are intermittently uncoupled from the ring gear 41, determined by 40 the positions of the crank portions 33 as they travel through their elliptical path. With the pistons rotating in fixed relation with and about the axes of the cylinder units and the piston crank portions 33 rotating through an elliptical 45 path, the piston crank portions 33 which at the moment are closer to the shaft 26 travel relatively slow while the other or outer pair of piston portions travel relatively fast. As a result, the ball clutch members 40 of the inner two pairs 50 of crank members 35 are wedged between the inner surface of the ring gear 41 and the outer tapered surfaces of the cranks coupling the two pairs of cranks to the ring gear. The other or outer pair of cranks increase in angular speed, 55 adjacent the major axis of the elliptical path, and traveling faster than the ring gear are uncoupled therefrom. As a result, the pairs of oppositely disposed piston portions 33 which at the moment are traveling at relatively slow peripheral speed are automatically coupled to the 60 driven ring gear 41 by their respective ball clutches 40 while the other pair of opposite piston portions and their cranks 35 have increased angular speed and are therefore uncoupled from the ring gear. As previously mentioned, the crank members 35 are individually connected to their respective pistons and are relatively movable to permit them to vary in angular speed to compensate for variations in speed of the crank portions 33 as they travel about the elliptical path. Thus, in the present pump, four cranks are coupled and two are uncoupled in each pumping unit at all times during operation. During operation of the pump, the piston portions 33 move toward 65 and away from the axis of the shaft portion 26

and rotate in their slide bearing members 38 and the pistons 32 are reciprocated to pump or compress fluid. Fluid is drawn in through the inlets 17, on the suction strokes of the piston, whence it passes through the arcuate passage 23 and 5 through the aligning ports 15 into some of the cylinders 12. The fluid is compressed by the pistons 32 after which the compressed fluid discharges into the outlet 17 when the ports 15 of the rotating cylinder units register with the arcuate outlet passage 24. The cylinder units are constantly rotating under the action of the piston 10 32 and the ports 15 are continuously aligning with the inlet passage 23 and then the outlet passage 24. 15

While I have shown and described my invention in detail it is to be understood that the same is to be limited only by the appended claims for many changes may be made without departing from the spirit and scope of the invention. 20

What I claim is:

1. A pump comprising, a cylinder arranged to rotate about an axis spaced from and substantially parallel with the longitudinal axis of the cylinder, an inlet and an outlet for said cylinder, a piston for said cylinder and having a crank portion externally of said cylinder, said portion being rotatable about an axis extending at an acute angle to the longitudinal axis of said cylinder to reciprocate said piston, said portion rotating through an elliptical path about said second-named axis, constant speed drive means for rotating said portion, and clutch means operatively connecting and disconnecting said drive means and said portion in accordance with variation of speed, said portion moving relative to said last-named means toward and away from said second-named axis in accordance with the elliptical path of travel of said portion. 30

2. In a pump, a plurality of radially spaced substantially parallel cylinders arranged for rotation about a common axis, a piston for each of said cylinders, inlets and outlets for said cylinders, said pistons having substantially parallel portions externally of said cylinders and extending at acute angles thereto, said portions being rotatable about an axis parallel thereto through an elliptical path to reciprocate said pistons, drive means, a plurality of individual driven members for said portions, said portions being individually movable relative to their respective driven members toward and away from said second-named axis, said driven members being relatively radially movable in accordance with variations in peripheral speed of said portions during their travel through said elliptical path, and slip clutch means operative to connect different driven members to said drive means in accordance with peripheral speed of said portions. 40

3. In a pump, a plurality of radially spaced substantially parallel cylinders arranged for rotation about a common axis, a piston for each of said cylinders, inlets and outlets for said cylinders, said pistons having substantially parallel portions externally of said cylinders and arranged to rotate about an axis extending at an acute angle to the axis of said cylinders, said portions rotating through an elliptical path, constant speed drive means to rotate said portions, and means operatively and individually connecting said portions and said drive means and compensating for variations in peripheral speed of said portions travelling through said elliptical path. 60

4. In a pump, a plurality of radially spaced 70

- substantially parallel cylinders arranged for rotation about a common axis, inlets and outlets for said cylinders, a piston for each of said cylinders, said pistons having substantially parallel portions externally of said cylinders and arranged to rotate about an axis extending at an acute angle to the axis of said cylinders, a shaft, said portions rotating through an elliptical path about the longitudinal axis of said shaft, constant speed drive means to rotate said portions, a plurality of radially extending clutch members individually mounted on said shaft and rotatably movable relative to each other, said clutch members being rotatable by said drive means, and means for connecting said portions to respective clutch members and movable relatively thereto and radially to the longitudinal axis of said shaft.
5. In a pump, a plurality of radially spaced substantially parallel cylinders arranged for rotation about a common axis, inlets and outlets for said cylinders, a piston for each of said cylinders, said pistons having substantially parallel portions externally of said cylinders and arranged to rotate about an axis extending at an acute angle to the axis of said cylinders, said portions rotating through an elliptical path, constant speed drive means to rotate said portions, said portions being individually movable toward and away from said second-named axis in accordance with travel through said elliptical path, and means successively coupling or uncoupling oppositely disposed portions to said drive means.
6. In a pump, a plurality of radially disposed parallel cylinders arranged to rotate about a common axis, inlets and outlets for said cylinders, a second plurality of radially disposed parallel cylinders arranged to rotate about a common axis at right angles to said first-named axis, a plurality of right angle pistons having their opposite end portions received in said cylinders, said pistons having parallel portions intermediate their ends extending at acute angles to said axes, drive means including a drum surrounding said second-named piston portions, a shaft around which said second-named piston portions rotate through an elliptical path, a plurality of hollow relatively movable spokes individually mounted on said shaft and extending radially therefrom toward the inner wall surface of said drum, means operable to successively couple and uncouple opposite pairs of spokes to said drum, and bearing members slideable in said hollow spokes and rotatably supporting said second-named piston portions.
7. A pump comprising, a pair of cylinders ar-
- ranged to rotate about axes relatively angularly disposed, a piston member having opposite end portions received respectively in said cylinders and having a crank portion intermediate the ends thereof, said crank portion being arranged to rotate through an elliptical path, drive means, a clutch member having a slideway extending radially of said axes and receiving said crank portion, and means cooperable with said clutch member for coupling and uncoupling said crank portion to said drive means in accordance with variations in speed of said crank portion as it travels said elliptical path.
8. In a pump, a plurality of radially spaced substantially parallel cylinders arranged for rotation about a common axis, a piston for each of said cylinders, inlets and outlets for each of said cylinders, said pistons having substantially parallel portions angularly disposed relative to said axis and rotatable through an elliptical path to reciprocate the pistons and rotate said cylinders, drive means, and a plurality of pairs of oppositely disposed slip clutches for operatively connecting said portions to said drive means, said opposite pairs of clutches consecutively clutching and unclutching respective pairs of said portions to said drive means as said portions travel said elliptical path and said portions being movable radially relative to their respective clutch members.
9. In a pump, a plurality of radially disposed parallel cylinders arranged to rotate about a common axis, inlets and outlets for said cylinders, a second plurality of radially disposed parallel cylinders arranged to rotate about a common axis angularly disposed to said first-named axis, a plurality of piston members having their opposite ends received respectively in said first and second-named plurality of cylinders, said pistons intermediate their ends having substantially parallel crank portions, a shaft substantially parallel to said crank portions and about which said crank portions rotate through an elliptical path, a plurality of pairs of oppositely disposed radially extending spokes individually mounted for rotation on said shaft relative to each other, said spokes respectively engaging said crank portions in sliding relation thereto so that said crank portions may move toward and away from said shaft as they travel through said elliptical path, a gear ring surrounding the outer ends of said spokes, and spring pressed clutch members carried in the outer ends of respective spokes and operable to clutch successively opposite spokes to said gear ring.

ROY STEVENS.
